UNITED STATES PATENT OFFICE

JAMES T. JONES, OF BRUNSWICK, GEORGIA, ASSIGNOR TO NORMAN A. WAY, CARLEY ZELMENOVITZ, AND ASHTON BURFORD, ALL OF BRUNSWICK, GEORGIA

APPARATUS FOR THE PRODUCTION OF GAS FROM GASOLINE

Application filed September 21, 1928. Serial No. 307,500.

This invention relates to an apparatus for the production of gas from gasoline and the object is to provide simple means whereby a constant supply of dry gas under pressure 5 may be available for use in a home or factory building or, by increasing the size and capacity of the apparatus, an entire community may be supplied with such gas.

Another object is to provide such an apparatus 10 having associated parts so related as to entirely avoid all danger from the gas and which may receive its gasoline and air supplies from without the building, the same being thoroughly mixed before entering the latter, and such entrance being effected by means which causes a suction through the system to 15 thoroughly break up the gasoline for intermingling with the air before being stored, under pressure, in a high pressure supply tank 20 within the building.

A further object is to provide in an apparatus of this character means for drawing the raw gasoline and the air into the system before the same enters the carbureting or 25 mixing chamber, the two elements being immediately caused to be drawn through breakers or baffles by means of the aforesaid suction and to enter said chamber in a semi-mixed condition for further mixing and drying before being drawn into the aforesaid 30 pressure tank; from which any wet mixture or condensation may be readily drawn to be returned to the gasoline tank.

A final object is to provide an apparatus 35 for the production of gas from gasoline which is of strong and durable construction having few parts to become worn or deranged and which requires no attention by an operator, the same being entirely automatic in its operation and adapted to cease operation when the 40 supply is at a predetermined point within the storage tank and to start operating when said supply falls to a predetermined point.

A full and complete understanding of the 45 invention may be obtained from a consideration of the following detailed description, taken in connection with the accompanying drawings forming a part of this specification; it being understood that while the drawings 50 show a practical form of the invention, the

latter is not to be confined to strict conformity with the showing thereof, but may be changed or modified, so long as such changes or modifications mark no material departure from the salient features of the invention, as pointed out in the appended claims.

In the drawings, in which similar reference characters designate corresponding parts throughout the several figures;

Figure 1 is a view in elevation showing the 60 complete apparatus;

Figure 2 is an enlarged vertical section through the carbureting chamber;

Figure 3 is a cross sectional view taken on the line 3—3 of Fig. 2;

Figure 4 is an enlarged vertical section 65 through the initial breaking or mixing chamber;

Figure 5 is a cross section through the 70 said breaking chamber, and

Figure 6 is a detail section, taken at right angles to Fig. 4.

Referring more particularly to Fig. 1 of the drawing, it will be seen that parts of the improved apparatus are adapted to be located within the building A while other connected parts are preferably located out-of-doors, beneath the ground level B, and at any desired distance from the building to insure safety.

A gasoline supply tank 1, forming part of the latter group, is equipped with the up-standing filler pipe 2 extending above the ground to supply the tank with gasoline from a truck or other source. The said filler pipe is preferably located adjacent to one end of the tank and has a suitable closure cap 3, while at the other end of the tank, preferably that adjacent to the building, there is located a carbureting chamber 4 in the form of a closed tank, separate from and considerably smaller than the tank 1 and located above the end of the latter.

The chamber 4 is connected to the adjacent end of the supply tank 1 by a pipe 5 which 95 communicates at one end with the side of the chamber and at the bottom thereof, and at the other end, with the top of the tank 1, as clearly shown in the drawing.

Entering the bottom of the tank 4, and at 100

the center thereof, is a mixture pipe 6 which extends considerably below the supply tank 1 and is provided with a return bend portion 7 terminating in the bottom of the tank and close to the adjacent end thereof.

5 The pipe 6 is provided with a union coupling 8 to facilitate the installation in the line of a baffle or breaking chamber 9 which is considerably smaller than the carbureting chamber and is located entirely below the supply tank. The chamber 9 is of cylindrical form, closed at each end and having threaded openings 10 in each end for connection with the pipe line 6 and is provided with 10 a plurality of vertically disposed sections or plates 11 of fine wire mesh arranged in touching relation and adapted to cause the incoming elements to be thoroughly broken up and intermingled as they are drawn by suction 15 through the same, in a manner to be described.

Connected to the pipe line 6 below the chamber 9, there is a short horizontal pipe 12 having elbow connection with an upstanding air pipe 13 which extends considerably above the ground level to insure a supply of fresh clean air and which is equipped with a pair of downwardly-extending elbows 14 to constitute inlet ports for the air.

20 Connected to the top of the tank 4 is a pipe 15, preferably located below the ground level and extending to and entering the building A where the same is connected to a compressor 16 of any suitable form for compressing 25 gas, said pipe line 15 having a main cut-off valve 17 included therein adjacent to the compressor and within the building for the purpose of cutting off the source of supply.

20 The compressor 16 is connected, by means 40 of a pipe 18 with a relatively large storage tank 19 preferably located within the building and having a capacity to suit the demand and strength to withstand the high pressure which it is desired to place on the 45 gas therein so that ample supply may be had at remote points.

The pipe 18 enters the tank 19 at the top thereof and is equipped with a pressure indicator 20 and a cut-off valve 21 for closing 50 to prevent back pressure when the tank is fully stored under pressure and the gas is to be conducted through the supply pipe 22 to the various points of consumption throughout the building. The pipe 22 is 55 connected to the pipe 18 at the top of the tank by a T-coupling 23 and a gas regulator 24 of any appropriate design is interposed in the pipe line 22 to properly regulate the flow of gas under pressure through said line.

60 The compressor 16 is adapted to be preferably driven by an ordinary electric motor 25 mounted on a common base with the compressor and adapted to be intermittently actuated when the pressure within the stor-

age tank 19 is reduced to a predetermined point by means of an automatic switch 26 interposed in the pipe line 18 and adapted to be actuated by a diaphragm (not shown) under the pressure within the pipe, to cut 70 in or out electrical energy through a source of supply 27 and to start or stop the motor 25 as the pressure within the tank 19 requires. No attempt has been made to illustrate the construction of the automatic electric switch, nor the gas regulator 24 in the drawings as such devices are on the market and well-known. A check valve 28 is interposed in the pipe line 18 between the automatic switch and the connection with the 75 compressor to prevent back pressure of the compressed gas from the tank 19 and through the compressor when the cut-off valve 17 is closed.

With the arrangements of the parts of 80 the apparatus as above described it will be seen that the gasoline and air is drawn through the system by means of suction, the air being caused to enter the ports 14 at a location where clean air is obtainable, the 90 admixture with the raw gasoline taking place at a point below the tank 1, so that the entire contents of the supply tank may be obtained and utilized. The gasoline and the fresh air are caused to be thoroughly broken up 95 and intermingled immediately at the point of juncture by means of the fine wire mesh in the breaking chamber 9 when they are drawn upwardly into the carbureting chamber 4. This chamber is of cylindrical form having 100 a closed top and bottom and the upper end of the pipe 6 is threaded where passing through said bottom and extends somewhat above the latter, as clearly shown in Fig. 2 of the drawings. A conical separating 105 chamber 29 is adjustably mounted on the upper end portion of the pipe 6 within the cylindrical casing 4, the upper end of the pipe extending close to the top or apex of the cone which is formed of sheet metal having 110 imperforate conical walls and a perforated bottom wall 30 located in a horizontal end of the pipe 6 and terminally secured to the conical and bottom walls, and providing an annular space around the upper end of the pipe 6 for the purpose of confining a 115 packing of mineral wool 32 or other similar material which completely fills the conical chamber and acts to further separate the mixture entering from the upper end of the pipe 6 and to force the admixture to pass through the wool and the perforated bottom 30, thence around the periphery of the cone, which is spaced from the walls 4 and through the space above which constitutes 120 a drying chamber, before entering the pipe 15. Any moist or wet gasoline which may 125 accumulate at the bottom of the casing 4 will gravitate through the pipe 5 back into the tank 1, and it will be observed that by 130

locating the breaking chamber below the supply tank a full supply of gasoline is assured at all times in the breaking chamber, located above the air inlet so that the air bubbles are thoroughly broken up thereby becoming thoroughly affiliated with the gasoline by the time the mixture enters the carbureting chamber. Any condensation or accumulation of wet gasoline that may occur at the bottom of the pressure tank 19 may be carried back to the gasoline tank 1 by means of a suitable pipe line (not shown).

From the foregoing, it will be seen that the apparatus is designed to provide a steady supply of dry gas to the point or points of consumption, the mixture being drawn through the system by suction and causing the gasoline to be thoroughly broken up and mixed with the air before entering the storage tank under pressure and that automatic means are employed to insure a constant replenishing of gas to the storage tank without the necessity for the manual operation of parts or other care of an attendant.

Having fully described my invention, and set forth its merits, what I claim is:—

1. In an apparatus for production of gas from gasoline, embodying a gasoline supply tank, a tank for storage of gas under pressure and a pipe line connecting the two tanks; a carbureting chamber interposed in the pipe line by which communication is established between the lower portion of the gasoline supply tank and the lower portion of said carbureting chamber, an air supply pipe in communication with the pipe line between the gasoline supply tank and carbureting chamber, and a gas compressor interposed in the pipe line between the carbureting chamber and gas storage tank, and operable to create suction to draw gasoline and air respectively, into the carbureting chamber and discharge resultant gas from said chamber under pressure to the gas storage tank.

2. In an apparatus for production of gas from gasoline embodying a gasoline supply tank, a second tank for storage of gas under pressure and having a pipe line connection with the gasoline supply tank; a carbureting chamber interposed in the pipe line adjacent to the gasoline supply tank and located at a higher elevation than said tank, said carbureting chamber comprising a hollow casing having a portion of the pipe line extending upward into the casing, a conical casing provided with a perforated bottom on said pipe line, the conical casing having a filling of mineral wool, and a compressor for drawing by suction gasoline and air into the carbureting chamber and through its mineral wool filling and directing the resulting gas to the gas storage tank.

3. In an apparatus for production of gas from gasoline, embodying a gasoline supply tank, a tank for storage of gas under

pressure, and a gas compressor having a pipe connection with the gasoline supply tank and the gas storage tank; a carbureting chamber having a pipe connection with the compressor and the gasoline supply tank, means for controlling the flow between the compressor and the gas storage tank and between the carburetor and compressor, respectively, means comprising mineral wool and a perforated plate within the carbureting chamber for subdividing liquid gasoline drawn through the carbureter by suction of the compressor, and means comprising a reticulated member in the pipe line between the gasoline tank and carbureting chamber for initially subdividing the raw gasoline and admitting air to the same prior to entrance into the carbureting chamber.

4. In an apparatus for converting gasoline into gas, embodying a gasoline supply tank, a gas storage tank and a gas compressor; a carbureting chamber interposed between the gas supply tank, and gas storage tank and located above the gasoline tank, a pipe line connecting the bottom of the gasoline supply tank with the bottom of the carbureting chamber, a pipe line connecting the top of the carbureting chamber with the compressor, a pipe line connecting the compressor with the top of the gas storage tank, an air supply pipe connected to the pipe line between the gas supply tank and the carbureting chamber, a tubular casing interposed in the pipe line between the gasoline supply tank and carbureting chamber and provided with a wire mesh filling to initially subdivide and mix the air and gasoline prior to entrance into the carbureting chamber.

In testimony whereof I affix my signature.
JAMES T. JONES.
